UNITED STATES PATENT OFFICE

172,117

COMBINED ILLUMINABLE HOUSE NUMBER SIGN AND DOOR BELL

Harry J. Wendling, Redondo Beach, Calif.

Application May 20, 1953, Serial No. 25,125

Term of patent 7 years

(Cl. D1—12)

To all whom it may concern:

Be it known that I, Harry J. Wendling, a citizen of the United States and resident of Redondo Beach, in the county of Los Angeles and State of California, have invented a new, original, and ornamental Design for a Combined Illuminable House Number Sign and Door Bell, of which the following is a specification, reference being had to the accompanying drawing, forming a part thereof.

Figure 1 is a perspective view of a combined illuminable house number sign and door bell showing my new design;

Figure 2 is a front elevational view;

Figure 3 is a side elevational view; and

Figure 4 is a bottom plan view.

I claim:

The ornamental design for a combined illuminable house number sign and door bell, substantially as shown.
